GUARD FOR ELECTRIC LAMPS

Ira E. Wright, Norfolk, Va.

Application February 18, 1949, Serial No. 77,179

6 Claims. (Cl. 240—102)

1

This invention relates to illumination and more particularly to a support and protective guard for a lamp of the type commonly employed with an extension cord and referred to as a "trouble lamp," and is a continuation-in-part of my co-pending application Serial No. 710,145, filed November 15, 1946, now abandoned.

Guards and mounting devices for lamps of this type have been in use for many years by mechanics and others in industry as well as in the home. In the past these have usually consisted of a wire cage having an opening at one end for the reception of the lamp socket. For certain kinds of work, cages of this type have been satisfactory, but for others, the protection afforded both to the lamp and to the user has been insufficient. Furthermore, the construction of the cages has been expensive because of the number of operations required in their production.

In certain industrial situations it is necessary to provide illumination in the presence of highly inflammable or explosive matter, including gases and volatile vapors of gasoline and the like. With the conventional lamp guard, the danger exists of a spark within the socket connection of the lamp, or in the event of the bulb's shattering, of the oxidation at high temperature of the lamp filaments, either of which may set off a fire or explosion.

Frequently, a lamp of this character is used to provide a large amount of illumination on a localized area and often an operator must have his face relatively close to the lamp, thus presenting a personal hazard if the bulb should be shattered.

Furthermore, lamps of this type are frequently used where they are subjected to steam, water, or other liquid or vapor from various sources, and unless some protection is provided the lamp is likely to become corroded, with the likelihood of a short circuit, and its life materially shortened.

Accordingly, it is an object of the present invention to provide a mount and lamp guard structure adapted to overcome the difficulties presented above.

A further object of the invention is the provision of a mount and lamp guard structure in which the socket and bulb are sealed within a protective housing in order to prevent the contact of the atmosphere or vapors in the space in which the lamp is to be used with the lamp or its electrical contacts.

A further object of the invention is the provision of a lamp support and guard which is

2

adapted to prevent the contact of moisture with the lamp on its socket.

A still further object of the invention is the provision of a housing for a lamp together with a reflector, and a guard for protecting the reflector, the housing, the lamp, and its component parts.

These and other objects of the invention will be apparent from the following description taken in conjunction with the accompanying drawings, wherein:

Fig. 1 is an elevation of the lamp guard;

Fig. 2, a section on the line 2—2 of Fig. 1;

Fig. 3, a bottom view of the structure shown in Fig. 1; and

Fig. 4, a top view of the structure shown in Fig. 1.

With continued reference to the drawings, a conventional lamp or bulb 10 is shown having a threaded contact portion 11 received in a socket 12 to which lead wires 13 are connected. The lamp and its socket are enclosed in a water and gas tight housing 14, comprising a cylinder or cup member 15 having a length substantially 20 that of the bulb 10 and an end wall 16 which is preferably curved to more nearly conform to the contour of the bulb.

The cup 15 may be of any suitable transparent or translucent material but a clear plastic has been found to be particularly suitable. The cup is provided at its other end with a lip or flanged portion 16 to which a gasket or sealing ring 17 is attached. An end closure member 18 for the cup consists of a substantially flat disk 19 with a flange 20 at its outer periphery and an upstanding cylindrical portion or collar 21 at its central portion, defining an aperture 22 for the reception of the socket 12.

The gasket 17 which is attached to the flange 20 of the cup 15 on one of its sides is attached at the other to the outer portion of the rim of the closure member 18, the overhanging flange 20 of the closure member abutting the peripheries of the flange 16 on its inner surface.

A gasket member 23 is positioned between the inner surface of the collar 21 and the socket 12, suitable sealing means being provided to form a gas and water tight connection. Various adhesives may be employed to hold the gaskets in place.

A reflector 24 is provided for the lamp and has a semi-cylindrical body portion 25 extending substantially the length of the cup 15, a reduced neck portion 26, and a collar or clamping member 27 adapted to encircle the collar 21 of the end

closure member 18 and clamp the collar tightly about the gasket 23 and for supporting the reflector on the housing 14. The lower end of the reflector has a flanged portion 25' adapted to anchor the reflector to the coil, later to be described.

The neck 21 has projections or ears 28 at its ends provided with apertures 29 for the reception of suitable fastening means such as a bolt or the like in order that the neck may be tightly drawn about the collar 21.

The cage or coil 30 is provided for protecting the lamp, its housing and the reflector against shock or impact and consists of a plurality of substantially helical convolutions of wire 31 forming a substantially cylindrical housing for the reflector 25 and sealed housing 14. The diameter of the coil is reduced at the neck portion 32 of the cage for adapting it to the reduced diameter of the socket collar and at the other end the last coil 32' of the cage is substantially at right angles to the axis of the coil.

For engaging and protecting the end 16 of the cup 15, a gate or clamping member 33 is provided and includes a pair of angular members 34 having end portions disposed at an angle to each other, the end portions 35 being connected by a strut 36 and having an upturned hook portion 37 adapted to clamp about the lowermost coil 32' of the cage. The arms 35 converge at a slight angle and the arms 34 at a much greater angle, the extremity of the arms 34 being provided with a loop 38 adapted to receive coil 32' for pivotal attachment of the gate 33 to the coil. After positioning the cage on the housing and reflector, the gate 33 is clamped shut, in which position the arms 34 and 35 resiliently urge the cup 15 against the gasket 17 to more firmly secure the connection.

A hook member 39 is attached to the side of the coil 30 by a longitudinal portion 40 and has a loop portion 41 projecting outwardly from the body portion 40.

It will be apparent that the present invention includes a support and housing for a lamp, the housing protecting the lamp, including its socket from contact with the elements and the gas or atmosphere in the space in which the lamp is used, and protects the user from the hazard of flying fragments of the bulb in case of its fracture, and from the danger of the ignition of inflammable and explosive substances in the vicinity from the presence of the lamp. The structure includes a reflector and a resilient cage-like protective housing for the assembly. Although the components of the lamp guard assembly are designed to be used together, the housing, the reflector, and the coil-like structure may be used separately if desired.

It will be obvious to those skilled in the art that various changes may be made in the invention without departing from the spirit and scope thereof and therefore the invention is not limited by that which is shown in the drawings and described in the specification but only as indicated in the appended claims.

What is claimed is:

1. A lamp assembly comprising a socket, a lamp engaged with the socket, and a housing for the lamp and socket, the housing comprising a non-porous, light transmitting cup, and an end closure member for the open end of the cup and having an upstanding collar receiving the socket; a reflector for the lamp comprising an elongated semi-cylindrical member adapted to partially

encompass the housing and having a clamping member at one end for receiving the collar of the housing; and a cage-like housing comprising a plurality of substantially helically arranged convolutions of wire and having a convolution of reduced diameter at one end for receiving the collar and clamping member, and a convolution at the other end in a plane substantially at right angles to the axis of the housing, and a gate member pivotally attached to the latter convolution, said gate member having an end clamping portion and a body portion adapted to resiliently urge the cup against the end closure member when the gate is in the closed position.

2. A guard for a lamp comprising a housing having a non-porous light transmitting cup and an end closure member for the open end of the cup, the end closure member having an upstanding collar adapted to receive a lamp socket; a reflector for the lamp comprising an elongated semi-cylindrical member adapted to partially encompass the housing and having a clamping member at one end for receiving the collar of the housing; and a cage-like housing comprising a plurality of substantially helically arranged convolutions of wire and having a convolution of reduced diameter at one end receiving the collar and clamping member, and a convolution at the other end in a plane substantially at right angles to the axis of the housing, and a gate member pivotally attached to the latter convolution, said gate member having an end clamping portion adapted to be resiliently clamped thereto, and a body portion adapted to resiliently urge the cup against the end closure member when the gate is in the closed position.

3. A guard for a lamp comprising a housing having a non-porous light transmitting cup and an end closure member for the open end of the cup, the end closure member having an upstanding collar adapted to receive a lamp socket; a reflector for the lamp adapted to partially encompass the housing and having a clamping member at one end for receiving the collar of the housing; and a cage-like housing comprising a plurality of convolutions of wire, and a gate member pivotally attached to an end convolution, said gate member having an end clamping portion adapted to be resiliently clamped thereto, and a body portion adapted to resiliently urge the cup against the end closure member when the gate is in the closed position.

4. A guard for a lamp comprising a housing having a light transmitting cup and an end closure member for the open end of the cup, the end closure member having an upstanding collar adapted to receive a lamp socket; a reflector for the lamp adapted to partially encompass the housing and having a clamping member at one end for receiving the collar of the housing; and a cage-like housing secured to said end closure member and comprising a plurality of convolutions of wire substantially surrounding said cup and reflector.

5. In a portable lamp guard, a cage-like wire housing comprising a plurality of convolutions of a helix, and a shield for a lamp having a collar portion adapted to be clamped on an electric lamp socket and an upturned flange portion adapted to engage the lowermost convolution of said helix for anchorage thereto.

6. A guard for a portable electric lamp comprising a cage-like wire housing wherein the housing comprises one continuous wire coil extending circumferentially about the lamp, a

shield for said lamp having a collar portion at one extremity adapted to be clamped on an electric lamp socket and about which the uppermost convolution of said coil is secured, and a looped flange portion at the other extremity adapted to engage the lowermost convolution of said coil to permit said coil to be anchored thereto.
